UNITED STATES PATENT OFFICE.

GEORGE H. BURPEE, OF PHILADELPHIA, PENNSYLVANIA, ASSIGNOR TO
FUEL ECONOMIZER COMPANY OF AMERICA, OF CAMDEN, NEW JERSEY,
A CORPORATION OF NEW JERSEY.

FUEL-ECONOMIZER.

SPECIFICATION forming part of Letters Patent No. 729,273, dated May 26, 1903.

Application filed May 23, 1902. Serial No. 108,717. (No model.)

To all whom it may concern:

Be it known that I, GEORGE H. BURPEE, a citizen of the United States, residing in Philadelphia, Pennsylvania, have invented certain 55
5 Improvements in Fuel-Economizers, of which the following is a specification.

My invention relates to certain improvements in the construction of fuel-economizers or feed-water heaters for boilers, which are 10 usually placed directly back of the boiler within the flue, so that the waste products of combustion will be utilized in heating the feed-water supplied to the boiler. These fuel-economizers or feed-water heaters are usually 15 constructed with upper and lower header-sections coupled together by vertical tubes, the upper header-sections being connected to the boiler and the lower sections being connected to the supply-pipe.

20 The main object of my invention is to so construct a fuel-economizer of this type that the products of combustion will be utilized to the best advantage.

A further object of my invention is to allow for the proper circulation of the water 25 through the economizer.

The invention also relates to certain improvements in details of construction described hereinafter.

30 In the accompanying drawings, Figure 1 is an end view of a fuel-economizer, partly in section, illustrating my invention. Fig. 2 is a side view, partly in section. Fig. 3 is a plan view. Fig. 4 is a sectional plan view on the line 4 4, Fig. 1. Fig. 5 is a sectional plan view on the line 5 5, Fig. 1.

AA are the lower headers of the fuel-economizer. These headers are made in sections, the number of sections depending upon the 40 size of the flue and the capacity of the boiler.

BB are the upper headers, arranged parallel with the lower headers.

Coupled to the upper and lower headers in any suitable manner are the vertical circulating-tubes C. In the present instance there is a single row of circulating-tubes coupled to each upper and lower header-section, as indicated in the drawings. Secured to the ends of the lower header-sections and common to all of these sections is a manifold D,

communicating with the supply-pipe for water to be heated.

The upper headers B are enlarged at b at one end, and in these enlargements are openings b', which form a common passage for all the header-sections, and this passage 55 communicates with the tube leading to the boiler.

In this type of fuel-economizer or feed-water heater the tubes are usually arranged in straight lines, so that the products of combustion will pass through the economizer between the tubes. By my improved economizer I arrange the alternate series of tubes so that they will be opposite the space between the other tubes, thus staggering the 65 tubes, so as to interrupt the passage of the products of combustion through the economizer, and thus utilize to a greater extent the heat from the products of combustion.

In order to economically produce a feed-water heater or economizer of this type, I so arrange the sections of the upper and lower headers that the series of upper headers will be identical in form, with the exception that the flange b² of one header will be shorter 70 than the flange b³ of the other header and the flange b⁴ at the opposite end of the header will be longer than the flange b⁵ of the adjoining header. This construction simplifies the manufacture of a fuel-economizer of this 75 type. The several sections are secured together by bolts or other suitable fastenings, and I preferably so shape each header that when the several headers are assembled, as in Fig. 3, the passage b', which forms a communication for the several upper headers, is in a straight line, as shown in Fig. 5, so as to insure the proper circulation of the water within the tubes and headers. Each upper header has side flanges b⁶, which when they 80 are assembled close the opening between the headers, as it will be seen that each of the headers is cylindrical except where they are coupled to the tubes.

Directly above each tube-opening of the 95 upper headers are openings e, slightly tapered, and inserted within the headers are caps E, which are held in place by bolts e', passing through cover-plates E', mounted on the outside of the header, so that on turning the bolt 100

the tapered caps E will be drawn tightly into the openings e , and thus make a tight joint.

In the extended portion b is an opening e^2 larger than the opening e . The object in making this opening larger is to allow for the introduction of the caps E within the header. This opening is covered by a cap E^2 , having a tapered flange and held in place by bolts e^3 .

Each upper header-section has a flange c on each side, to which the plates F F forming the casing of the economizer are secured, as shown in Figs. 1 and 3.

The lower series of headers A are supported in the present instance on I-beams F', forming the base of the economizer, and the space W between these beams is utilized for the accumulation of soot, which is scraped from the tubes.

The lower header-sections A are so spaced apart as to allow a passage w between each section for the soot, so that as the soot is removed from the surface of the tubes C it passes down between the headers into the chamber W.

Each header-section A has an opening a at one end, which communicates with the manifold D, so that each lower header is supplied directly with water from the manifold. Surrounding this opening a is a tapered flange a' , fitting tapered openings in the manifold D, as shown clearly in Fig. 1. This manifold D is supported on brackets F², attached to one of the I-beams F', and the casings F F extend from the upper surface of each I-beam to the upper headers B, as described above, the casings being cut away for the manifold D. Thus the lower headers and one end of the upper headers, as well as the circulating-tubes, are inclosed within the casing, while the manifold D is mounted outside the casing, and the upper portions of the upper headers are also on the outside of the casing, so that in the event of any leak or in the case of repairs to these parts it is not necessary to enter the chamber, but access may be had to these parts from the exterior.

In the manifold D, directly opposite each opening a , is an opening d , having tapered walls, and these openings are covered by caps d' , having tapered flanges d^2 , which fit the tapered walls of the openings. It will be noticed that these caps are made in the peculiar form shown in Fig. 2, having extensions d^3 at each end through which the securing-bolts pass. These securing-bolts g pass through extensions d^3 of the cap, through the flanges d^4 on the manifold, and their heads rest in pockets a^3 on the header-sections A.

The upper pockets are arranged on one side of a vertical center line, and the lower pockets are arranged on the opposite side of the vertical centerline, so that the caps are arranged at an angle, as shown in Fig. 2. This construction reduces the height of the manifold and the lower headers, as well as allows more room for the reception of the bolt in the sockets a^3 .

The lower headers A are similar in form, with the exception that the body is extended at one end of the alternate extensions and extended on the opposite end of the other section, as clearly shown in Fig. 4.

The fuel-economizer is placed in the flue leading from a boiler or other furnace in the present instance, so that the upper and lower headers are arranged transversely to the direction of the products of combustion. The manifold D is coupled to the water-supply pipe, and the opening b' in one end of the upper headers is coupled to the tube leading to the boiler. The casing incloses the tubes and a portion of the upper and lower headers, and as the products of combustion pass through the economizer their free passage is interrupted by the staggering of the tubes. Thus while the products of combustion pass through the economizer the heat from the products of combustion is utilized to effect the best results.

I claim as my invention—

1. The combination in a fuel-economizer, of a series of upper and lower headers placed side by side, each of said headers having a series of openings, vertical tubes entering the openings and connecting the upper and lower headers, the lines of the openings in the alternate headers being in series of planes parallel to the lines of the openings in the remaining headers whereby the tubes of one series are staggered in respect to those of the other series so that the passage of the products of combustion through the economizer will be interrupted, substantially as described.

2. The combination in a fuel-economizer, of a series of upper header-sections, a series of lower header-sections, and a series of circulating-tubes coupled to the upper and lower header-sections, the tubes of one section being staggered in respect to the tubes of an adjoining section, the alternate upper header-sections having extended flanges at one end, and the other sections having extended flanges at the opposite end, so that when the several upper sections are assembled the tubes of one section will be opposite the spaces between the tubes of an adjoining section, substantially as described.

3. The combination in a series of upper header-sections, of a fuel-economizer, each section having a series of openings to which the tubes are attached, a series of openings in the upper portion of the header in line with the tube-openings, caps for said openings, each header-section being enlarged at one end and having an enlarged opening therein, a cap therefor, and openings in the sides of the enlarged portion of each header-section arranged off center so that when the said header-sections are coupled together the tubes will be staggered and the openings forming communication between one section and the other will be in a straight line, substantially as described.

4. The combination in a fuel-economizer, of the upper headers, circulating-tubes coupled to the said headers, a series of lower header-sections placed side by side and having tube-openings in their upper portions, the tube-openings of one header alternating with the tube-openings of the adjoining header, a longitudinal manifold coupled to the several lower header-sections, openings in the longitudinal manifold opposite the opening in each header-section, cap-plates for said openings, with means for securing the cap-plates to the longitudinal manifold, said fastenings being arranged off the vertical center line, substantially as described.
5. The combination in a fuel-economizer, of upper header-sections, lower header-sections, a series of vertical circulating-tubes coupled to the upper and lower header-sections, the tubes being staggered so as to interrupt the passage of the products of combustion through the economizer, a longitudinally-arranged manifold coupled to the lower header-sections, each upper header-section having side openings so arranged that when the several sections are coupled together there will be a straight passage forming a com-

munication between the several upper sections, and a straight passage forming communication between the several lower sections, substantially as described.

6. The combination in a fuel-economizer, of a series of upper header-sections, a series of lower header-sections, vertical circulating-tubes connecting the upper header-sections with the lower header-sections, a longitudinal manifold coupled to the ends of the lower header-sections, openings in the longitudinal manifold-section opposite the end of each lower header-section, caps for said tubes, bolts passing through the caps of the longitudinal manifold-section and secured to projections on each lower header-section, the said bolts and projections being arranged at one side of a vertical line drawn through the lower header-sections, substantially as described.

In testimony whereof I have signed my name to this specification in the presence of two subscribing witnesses.
